METHOD OF FORMING BRAKE DRUMS

Jewell W. Vanderveer, Syracuse, N. Y.

Application April 22, 1931, Serial No. 531,889

1 Claim. (Cl. 29—152.2)

Brake drums have heretofore been made all of cast metal, that is, the brake ring and the disc supporting it. It has also been proposed to make brake drums provided with a cast ring and a sheet metal disc supporting the ring, the connection between the disc and the ring being accomplished in the casting operation. This forms a desirable brake drum, but is subject to serious losses through strains set up in the cooling of the cast ring with relation to the sheet metal disc. The present invention is designed to form brake drums utilizing a sheet metal disc and a cast ring connecting them in a simple, but substantial manner without placing the ring under objectionable strains. Features and details of the invention will appear from the specification and claim.

A preferred embodiment of the invention and manner of forming the same is illustrated in the accompanying drawing as follows:—

20 Fig. 1 is a section on the line 1—1 in Fig. 2.

Fig. 2 a side elevation of the drum.

Fig. 3 an elevation of an attaching plug.

Fig. 4 a central section of a modification.

Fig. 5 a mold showing the manner of forming 25 the ring illustrated in Fig. 4.

1 marks the brake ring. This has an internal rib 2 on its inner periphery, this rib having slight enlargements at 3 and being provided with perforations, or openings 4. These openings are 30 countersunk forming a shoulder 5.

A sheet metal disc 6 is struck up having the usual annular shoulders and being adapted for the usual mounting. It is preferably of sheet steel, or at least weldable material.

35

The disc seats against the rib 2. A plug 7 is arranged in the opening 4, the plug preferably conforming to the shape of the opening and is secured to the disc by spot welding, the spot welding being accomplished as indicated by the electrodes 8. The plug 7 may be made in a single piece, or it may be in the form of two punched discs, the spot welding not only uniting the plug with the disc 6, but also uniting the parts of the lug. By this arrangement, the ring 1 may be 65 cast and is free from shrinkage strains, turned accurately and provided with the disc without introducing strains to the structure. Thus a cast brake drum with its advantages particularly as to scoring and as to chatter may be accomplished in 70 a cheap and reliable manner in that the losses in production are very slight and the ring is stronger in use in that it does not have initial strains.

In the modified form in Fig. 4 the brake ring 9 has an internal rib 10. In the casting of this rib 75 the plugs 11 of weldable material are placed in the mold, as shown in Fig. 5, and secured in the rib 10 in the casting operation. Otherwise the structure is similar to that shown in Fig. 1. The disc 6 is seated against the rib 10 and the plug 11 is welded to the disc by spot welding through the electrodes 8.

What I claim as new is:—

The method of forming a brake drum which consists in shaping a metal disc of weldable 85 material, casting a brake ring around a connecting piece, and welding said piece to said disc.
